Inventor:

Catherine O'Hara.

UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A LADY'S WALKING-SKIRT.

SPECIFICATION forming part of Design No. 14,449, dated November 27, 1883.

Application filed September 26, 1883. Term of patent 3½ years.

To all whom it may concern:

Be it known that I, CATHERINE O'HARA, of the city, county, and State of New York, have invented and produced a new and original Design for a Pattern of a Lady's Walking-Skirt, (numbered 8,902;) and I do hereby declare that the engraved prints accompanying this specification convey to any one accustomed to using paper patterns a clear understanding of how a garment made up by the pattern will appear.

The design combines a short walking-skirt, a lower front drapery that extends nearly to the bottom of the skirt, showing center and side panels and plaited fans between them, the

side panels being shown turned back in *revers* 15 at their front edges, a short apron-drapery showing plaits at its back edges, and a deep full back drapery displaying plaits at its front edges and showing tackings at the center.

What I claim as my invention, and desire to 20 secure by Letters Patent, is—

The design for a lady's walking-skirt, as shown in the engraved prints accompanying this specification.

CATHERINE O'HARA.
